BOOM FOR SHOVEL EXCAVATORS.

Application filed December 31, 1924, Serial No. 759,178, and in Germany January 4, 1924.

In the operation of shovel excavators it frequently occurs that the shovel or bucket untimely, that is to say before the excavator has finished its rotative or swinging movement, strikes the ground, thus subjecting the parts and mechanisms of the excavators to strains and shocks, which they cannot stand and which lead to breakages. To meet this inconvenience by increasing the strength of the parts, is not sufficient since the increased weight inherent therewith will also increase the inertia of the swinging parts.

The object of the present invention is to overcome these difficulties by a novel construction.

This task is solved by mounting the boom rotatably on the base plate which is carried oscillatorily about a horizontal line by a rotative part of the excavator in such manner that it is adapted to rotate about its longitudinal axis. By the aid of a double acting spring or by two springs the boom is yieldingly held in its central position, or pulled back in this position after oscillating to one side or the other.

In Fig. 1 an elevation is shown of the lower part of an excavator derrick or boom.

Fig. 2 is a plan view partly broken off, and

Fig. 3 a view of the same shown in the direction of the arrows in Figs. 1 and 2.

Figs. 4 and 5 are views similar to Fig. 3, showing the parts when the boom has rotated on its longitudinal axis.

The boom *a* is mounted rotatively by a pivot pin *b* on the base plate *c* and is provided with lateral feet *d* resting on the base plate which itself is connected rotatably about a horizontal axis by end studs *e* to the upper truck *A* of the excavator. Bearing plates *d'* may be attached to the base plate *c* for allowing the feet *d* to bear against. When the bucket or shovel is operated to execute a new cut into the ground to be excavated and strikes against a hard hindrance the possibility is given that the rotative part of the excavator continues its rotative movement for a certain angle on account of the rotatability of the boom *a* about its longitudinal axis, that is to say about the pivot pin *b*. There is no difficulty in arranging the parts in such manner that the angle about which the rotatable parts of the ex-

cavator can rotate when continuing the said rotation may become so large that the rotative parts of the excavator in reaching such angle, completely lose their impetus by the action of the usual rotation brake (not shown) present in all shovel excavators. The result of this is, that all injurious overstrainings or stresses are relieved from the shovel beam, the derrick and the rotary upper-part of the excavator. A sudden deadening of the inertia of rotary parts is thus not necessary, but retarding pressures are kept within such limits that they can be overcome by the usual rotation brake.

If desired the boom *a* may be connected with retraction springs, which pull the boom back into its central position. In the construction shown a helical spring *g* is arranged within a casing *f*, one end of the spring pressing against an end wall *h* of the casing and the other end against a disk *i*, connected to a drawrod *k*. This rod is connected at its end projecting out through the end wall *h* with an arm *m* of a bell crank lever *m*, *n* pivoted to the derrick or boom by the pin *j*, the other arm *n* of which lever being connected with the base plate *c* by a link *o* and a pin and slot connection as shown. The end wall *h'* opposite the end wall *h* has an arm *k'* in line with the tension rod *k*. Pivoted connected with this arm *k'* is the arm *m'* of the bell crank lever *m'*, *n'*, the arm *n'* of which being also connected with the base plate *c* by a link *o'*. The parts *o*, *n*, *m* and *j* are similar to the parts *o*, *n*, *m* and *j* on the other side. The spring or springs *g* must be so powerful, that they can overcome the friction of the boom feet *d* on the base plate *c* or bearing plates *d'* respectively. They increase the effect of the rotation brake by the fact that the spring which is compressed by the rotation of the boom about the pivot pin *b*, exerts a moment of retardation on the rotary parts of the upper truck of the excavator in the same direction as the rotation brake. The spring and the rotation brake must be so dimensioned that the total effect of both parts is not too great. The use of one or two springs has the advantage that they hold the boom, even when excavating, in its central position. It may happen that the lateral forces, which arise on the shovel while the excavator is digging, will increase

to such an extent that the shovel gives way laterally, thereby turning or twisting the boom about its longitudinal axis. To prevent this twisting of the boom becoming too extensive, it is advisable to limit such turning by stops p and p' against which the links o , o' contact.

If the boom, on rotation of the excavator and the shovel, strikes the ground and rotates, for instance, to the position shown in Fig. 4 the pin j will have moved upwardly and the pin j' downwardly. Consequently the bell-crank lever m , n has been given a clockwise rotation by the link o , while the bell-crank lever m' , n' , even when the lost motion in the pin and slot connection has been overcome, cannot rotate owing to the arm m' striking against the stop p' . It results that the distance between the ends of the arms m and m' is increased and the spring g pressed together owing to the disk i being pulled towards the end wall h of the casing f . The strain of the spring then tends to return the bell-crank lever m , n into its former position, by pulling the pin j downwardly and rotating the boom backwardly.

When the boom is rotated into the position shown in Fig. 5 the bell-crank lever m' , n' is rotated in a counter-clockwise direction owing to the pin j' having moved upwardly, while the bell-crank lever m , n is prevented from rotating by abutting against the stop p . Here again the distance between the ends of the arms m and m' is increased, the arm m' having pulled the arm k' and with it the casing f to thus move the end wall h towards the disk i and thus to again compress the spring g , which tends to turn the bell-crank lever m' , n' , and by means of the pin j' , the boom, back into its former position again.

The novel construction has not only advantages that are efficient when the shovel is starting to dig, but also such, which are effective while digging. As has been explained when excavating frequently lateral

pressures arise on the shovel. When the pressure is slowly increasing the rotary part of the excavator has time to give way by turning to one side. When however the pressure occurs suddenly the inertia of the rotating parts of the excavator is so great that they cannot follow quickly enough. Then the side pressure will exert a bending strain within the shovel beam and a rotary strain in the boom or derrick and such strains may lead to ruptures.

Arranging the boom to rotate about its longitudinal axis has moreover the advantage, that on side pressures arising suddenly overstrainings or stresses are avoided, because the rotary part of the excavator need not be made to rotate suddenly, but quite by degrees by the gradually increasing pressure of the compressed spring, which exerts the rotary moment on the rotary parts of the excavator.

I claim:

1. A boom for shovel excavators, comprising, a base plate journaled oscillatorily about a horizontal axis on a rotary part of the excavator, and a pivot mounting the boom on the base plate for rotation about the longitudinal axis of the boom, and means including a double acting spring and bell-crank levers cooperating therewith for biasing the boom about its pivot to its central position on the base plate.

2. A boom for shovel excavators, comprising, a base plate journaled oscillatorily about a horizontal axis on a rotary part of the excavator, and a pivot mounting the boom on the base plate for rotation about the longitudinal axis of the boom, and a double acting spring arranged to bias the boom about its pivot to its central position on the base plate, bell crank levers connected at their central points to the foot of the boom, each bell crank lever having its two ends operatively connected respectively to the base plate and to one end of the double acting spring.

HANS FRIEDRICH MENCK.
